RAILWAY LOCOMOTIVE PISTON VALVE
INERTIA ARRESTER

Carl G. Ash, Pomona, Calif.

Application January 16, 1941, Serial No. 374,741

6 Claims. (Cl. 121—161)

This invention relates to improvements in means for arresting the inertia of railway locomotive piston valves.

The primary object of this invention is the provision of improved means for cushioning the shock of the steam control piston valves of railway locomotive driving equipment incident to stopping, starting and reversing of the piston valve whereby to do away with many of the troubles incident to present day locomotive railway piston valve operation.

It is well known to those skilled in the art relating to railway locomotive driving and operating mechanism that the shock incident to operation of piston valves occasions frequent failure of parts of the valve gearing; causes excessive wear of the pins and bushings of the valve gear and other operating equipment; causes excessive trouble with the reverse gearing, and is a direct fault of many accidents to life and property. It is the purpose of my invention to arrest the inertia of the piston valve with an improved cushioning arrangement at each end of the travel stroke of the valve, working at short travel at high speed, whereby the above mentioned deficiencies of conventional railway locomotive operation will be overcome; the locomotive action will be more efficient and there will be a substantial saving in fuel and water consumption, by better control of cut off at speeds.

Other objects and advantages of this invention will be apparent during the course of the following detailed description.

In the accompanying drawings, forming a part of this specification and wherein similar reference characters designate corresponding parts throughout the several views.

Figure 1 is a fragmentary view, partly in section, showing the valve gearing and drive connections of a conventional steam railway locomotive, with my improved inertia arrester associated therewith.

Figure 2 is a cross sectional view taken thru a railway locomotive piston valve in association with the main piston assembly of the locomotive, and showing my improved inertia arrester associated therewith, for a short travel of the piston valve, with the valve in forward position.

Figure 3 is a view of parts similar to that shown in Figure 2, but with the piston valve in rear position, for short travel.

Figure 4 is a cross sectional view of the parts shown in Figure 2, but with the piston valve arranged for full length travel, with the valve in forward position.

Figure 5 is a cross sectional view of the parts shown in Figure 4, but with the piston valve in position for full travel, and in rear position.

Figure 6 is a longitudinal cross sectional view taken thru the steam control piston valve and showing its association with improved inertia arrester pistons.

In the drawings, wherein for the purpose is shown only a preferred embodiment of the invention, the letter A may generally designate a railway locomotive which may include a main piston assembly B connected with means C to drive the wheels D of the locomotive. A piston steam control valve assembly E is provided in association with the main piston cylinder for control of steam with respect thereto, as is well known to those skilled in the art. In association with the piston valve E and the driving means C, there is provided valve gearing F of any approved type (Baker shown in the drawings). In connection with the piston valve mechanism I associate my improved inertia arresting means G.

The main piston 10 of the piston assemblage B operates within a cylinder 11 and is provided with a piston rod 12 connected with a conventional cross head 13. The latter has connected therewith a connecting rod 14 forming part of the drive means C, which is connected to the main crank 15.

The body or piston valve 20 of the piston valve assemblage E operates within a cylinder 21 having bushings or liners 22 and 23 within which the piston valve enlarged ends 24 and 25 of the piston valve, upon which there is admission and exhaust rings, respectively operate to control steam ports 27 and 28 respectively for operation of the main piston of the locomotive, in a manner which is purely conventional.

The valve gearing F includes a valve rod 30 pivotally connected to a combination lever 31; the latter in turn being connected with a valve stem cross head 32 which is connected by a suitable rod 33 with the piston valve body 20, in a manner to be subsequently described. The valve rod 30 is pivotally connected with a bell crank 35 and thru suitable reversing yokes 36 is connected with a gear reach rod 37. This bell crank is also connected with a gear connecting rod 40 and an eccentric rod 41 connected at 42 to the crank arm of the main crank of the drive mechanism C.

Referring to the improved inertia arrester construction G, I provide inertia piston cylinder extensions 60 and 61 upon the ends of the usual piston valve cylinder 21. To accomplish this the

cap plates at the ends of the usual piston valve cylinder are removed and the inertia piston cylinders 60 and 61 are secured by means of studs or bolts 62 in the usual cap plate attaching bolt openings. The cylinder 61 may be referred to as the forward inertia arresting cylinder and it may have a cap plate 63 secured in place by bolts 64, as shown in the drawings. The outer end of the other inertia piston cylinder 60 is provided with an end plate 65 secured at 66a, and provided with a suitable stuffing box 66 thru which the valve stem 33 extends.

Referring at this time to a detailed description of the piston valve construction and assemblage, the valve body 20 is provided with enlarged ends 24 and 25 each having the piston valve admission and exhaust rings. The valve body itself is hollow. The valve stem piston rod 33 is extended thru suitable hubs 20a attached in spider-like manner to the enlarged ends of the piston body 20. Suitable sleeves 72 and 73 are provided upon the rear and fore ends of the valve stem piston rod 33, and on the extreme forward end of the latter, at the end of the sleeve 73 there is provided a cushioning or inertia arresting piston 75, which is relatively thin and externally provided with a piston ring thereon. The sleeve 72, which is preferably of the same length as the sleeve 73 at its rear end is similarly provided with a cushioning or piston valve inertia arresting piston head 76 of the same construction as the cushioning piston 75. An integral flange 77 on the rod 33 holds the valves 20, 77 and 76 in a definitely spaced rigid assembly, such as shown in Figure 6.

The piston valve 20 of course, operates only in the piston valve chamber cylinder 21 and controls the ports 27 and 28. On the other hand, the cushioning pistons 76 and 75 respectively operate in the chambers of the inertia arrester cushioning cylinders 60 and 61 respectively.

It is to be noted that the cylinders 60 and 61 provide cushioning compartments therein between the end plates 65 and 63 thereof and the cushioning pistons which operate respectively therein. Each cylinder 60 and 61 is, however, provided with a by-pass. These by-passes are indicated at 80 and 81 respectively for the cylinders 60 and 61, and they have conduits which connect in the chamber of their respective cylinders at opposite sides of the over-all path of travel of the respective cushioning pistons operating therein.

The respective by-passes 80 and 81 are provided therein with by-pass valves 83 and 84 respectively, the valve heads 85 of which are normally maintained open by means of springs 86. A compressed air line 87 communicates with both of the by-pass valves and upon application of pressure the air piston is forced downward and springs 86 will be compressed, as will be apparent from Figure 2 of the drawings, and close the valves 85 upon their seats in the casing of the respective by-pass valves in order to close off communication of each of the by-pass lines 80 and 81, so that there is no connection between the chamber portions of the inertia arrester cylinders at opposite sides of the cushioning pistons respectively operating therein.

The compressed air line 87 receives its air from a suitable tank 88, and a control valve 89 may be positioned in the line 87, under control of the engineer. This valve 89 has a valve head provided with three ways therein. Two of them may communicate opposite sides of the line 87,

and in another position closes the line 87 from the reservoir 88 and opens the line 87 between the valve 89 and the by-pass valves 83 and 84 to an escape nozzle or opening 90 provided in the casing of the valve 89 so that air under pressure in the line 87 may be exhausted therefrom and allow valves 85 to be unseated, thereby establish communication between outer ends of inertia cylinders and the exhaust passages K, allowing steam in cushioning end of inertia cylinder to pass to exhaust passage, when its locomotive is working at long valve travel, as at low speed, and cushioning is not desired.

In conventional railway steam locomotive operation, it is customary through the valve gearing to provide for a long piston valve travel, such as when starting the locomotive with a heavy train, or when pulling the load of the train over heavy grades. Also, a short valve travel is provided when the locomotive approaches top speeds. For short valve travel of the piston valve 20 cushioning effects are provided by the cushioning pistons 75 and 76, according to the length of the travel in their respective pistons, but for long piston valve travel, since the cushioning pistons 75 and 76 closely approach the end plates 63 and 65 respectively associated therewith, means is provided to vent some of the compressed steam from the cushioning cylinders between the pistons 75 and 76 and the end plates into the spaces between the cushioning pistons and the piston valve 20 as relief or protection. To that end the liner of each of the cushioning cylinders 60 and 61 is provided with a plurality of ducts 100 adjacent the end plates 63 and 65 and extending a short distance therefrom and terminating short of the position which the cushioning piston operating therein will occupy at the end of the short valve travel, but extending sufficiently far so that the end thereof will be uncovered at the end of the cushioning piston in long valve travel for permitting escape of compressed steam between the cushioning pistons and their respective cushioning cylinder heads while locomotive is worked at long travel. The short valve travel of these cushioning pistons is well shown in Figures 2 and 3 of the drawings, and long valve travel of these cushioning pistons is shown in Figures 4 and 5 of drawings.

In order to compensate for pressure differentials at the opposite sides of each of the cushioning pistons, their respective cylinder liners are also provided with vent ducts 101 at the inner ends of their movements, to permit of by-passing exhaust steam pressure under conditions of short and long valve travel in a manner which will be apparent from the foregoing description.

In Figure 2 of the drawings where the parts are set for a short valve travel of the cushioning pistons, the forward cushioning piston 75 has reached its forward limit of movement and the steam between this piston 75 and the end plate 63 has been compressed several ratios above exhaust steam pressures in exhaust steam passages K, thereby cushioning piston valve 20. Also trapped compressed exhaust steam in cylinder 61 will assist in starting valve 20 in opposite direction, since the valve 85 is closed. The operation of the other cushioning piston 76 is exactly the reverse, as shown in Figures 2 and 3.

For a long valve travel of the cushioning pistons, as shown in Figure 4, the cushioning piston 75 operates against little or no steam pressure between piston and the end plate 63, for no buffering is necessary at slow speeds, with long travel.

Since at long travel and slow speeds the inertia is nil. Any steam compressed in this space by reason of long valve travel operation, if the valves 85 should not be open will be permitted to escape to the rear side of the piston 75, since the ports 100 will be uncovered as piston 75 nears the extremity of forward movement of the piston 75, as shown in Figure 4. The piston 76 of course, operates in a position opposite to the piston 75 with respect to the vent control ports 100 and 101. As shown in Figures 4 and 5, the by-pass valves are preferably open for long piston valve travel.

From the foregoing, it is apparent that it is in the last half of the piston valve travel, while the piston valve is operating at short travel, at high speeds that the cushioning is desirous and needed to arrest the inertia of the heavy piston valve, and the compressed exhaust steam that cushions the piston valve will assist in starting the piston valve in the reverse direction thereby relieving the valve gears of heavy pressure during the power thrusts that start the piston valve from standing position when the conventional type of piston valve is used.

The advantages resulting from the improved arrangement of impact cushioning means at each end of the piston valve chamber will be apparent to those who are familiar with locomotive piston valve operation. Incident to gear reversing, the impact upon the reverse gearing is many times the force of the impact of the piston valve. When this force strikes the reversing motor, the reverse gearing has caught up with its work and is at rest, so that it receives the full force of the impact, before the piston, now moving, can actuate the necessary valves and parts to admit air to the air cylinder of the reverse gears. The air piston of the reversing gearing has moved against the air in the opposite end of the cylinder with such speed and power that the air is compressed, allowing the air reverse piston to continue to the point where the machinery is placed in reverse motion while the locomotive is running forward. This is a dangerous condition and is entirely eliminated with the improved inertia arresting means of this invention.

As a further means of pointing out the importance of the present invention, we may take a conventional locomotive having an eighty-four inch diameter driving wheel. It is not unusual for such a locomotive to run at speeds of 120 miles per hour. This means that there are eight revolutions per second of the driver wheel. The valves of the locomotive must admit steam to each end of the steam cylinder of the locomotive, and exhaust steam from each end one time for each revolution of the drive wheel. This means four admissions and four exhausts for each revolution of the drive wheel and eight revolutions per second totals thirty-two admissions and thirty-two exhausts per second. The wear and tear upon the parts occasioned by starting, stopping and reversing the piston valve under such conditions is apparent, and the desirability of cushioning the force and the improvement resulting from the inertia arrester of the present invention is correspondingly apparent.

In addition to the advantages above enumerated, the cushioning arrangement of the present invention provides for cushioning the piston valve; enabling the compressed steam that cushions the piston valve to assist in the reversing direction after being stopped; prevents the reversing of the valve gears when the locomotive is

running at high speeds at short cut-offs; caused by inertia of heavy piston valves enables the engineer to operate the locomotive at the proper cut-off without danger of the valve gears being reversed; enables the piston valve to be maintained in a proper plane, thus eliminating frequent reboring operations of valve chamber bushings; eliminates excessive locomotive vibration at high speeds; improves riding quality of the locomotives, and does away with impacts delivered to cross-heads, thereby reducing maintenance cost.

Various changes in the shape, size and arrangement of parts may be made to the form of invention herein shown and described, without departing from the spirit of the invention or the scope of the following claims.

I claim:

1. In a piston valve inertia arrester for railway steam locomotive operating equipment, the combination of a piston valve, a piston valve cylinder therefor, a cushioning piston connected with the piston valve, a cushioning piston cylinder within which the cushioning piston operates, means for by-passing exhaust steam in the cushioning cylinder from one side of the cushioning piston therein to the other side at each end of the stroke movement of the cushioning piston, and means for adjusting the cushioning pressure.

2. In a piston valve steam control assemblage for the operating equipment of railway steam locomotives, the combination of a piston valve, a piston valve chamber, cushioning pistons secured rigidly with the piston valve in spaced relation at each end thereof, cushioning piston cylinders within which each of the cushioning pistons operates, by-passes connected with each of the cushioning cylinders, each by-pass being connected for by-passing pressure from one side of the cushioning piston in the cushioning cylinder to the opposite side of that particular cushioning piston, control valves in each of said by-passes, and means for opening or closing said valves to permit of by-passing pressures when not needed.

3. In a piston valve steam control assemblage for the operating equipment of railway steam locomotives, the combination of a piston valve, a piston valve chamber, cushioning pistons secured rigidly with the piston valve in spaced relation at each end thereof, cushioning piston cylinders within which each of the cushioning pistons operates, by-passes connected with each of the cushioning cylinders, each by-pass being connected for by-passing pressure from one side of the cushioning piston in the cushioning cylinder to the opposite side of that particular cushioning piston, control valves in each of said by-passes, and means for opening or closing said valves to permit of by-passing pressures when not needed and other means formed in the cushioning piston cylinders for by-passing cushioning pressure from one side of the cushioning pistons acting therein to the other side thereof as the cushioning pistons approach the end of the piston valve stroke movement during long valve travel when the by-pass valves are closed.

4. In railway steam locomotive operating equipment, the combination of a steam regulating piston valve, a piston valve chamber therefor having steam control ports, a cushioning piston connected with the piston valve, a cushioning piston chamber in which the cushioning piston operates, a by-pass connected with the cushioning

piston chamber, for by-passing and admitting exhaust steam under pressure to the cushioning piston chamber at the extremities of movement of the cushioning piston operating therein, valve means in the by-pass for controlling passage of exhaust steam pressures from the cushioning end of the cushion piston chamber when cushioning is not needed, and other by-pass ducts in the cushioning piston chamber disposed at the compression end of the cushioning piston chamber and adapted to be uncovered for passing pressures from one side of the cushioning piston to the other side thereof in said chamber as the cushioning piston approaches the extremities of its movement at long valve travel when cushioning is not needed.

5. In a piston valve inertia arrester for railway steam locomotive operating equipment, the combination of a piston valve, a piston valve cylinder therefor, a cushioning piston connected with the piston valve, a cushioning piston cylin-

der within which the cushioning piston operates, means for by-passing pressures from one side of the cushioning piston to the other side of the cushioning piston within said cushioning piston cylinder, and valve means for controlling said by-pass.

6. In a piston valve inertia arrester for railway steam locomotive operating equipment, the combination of a piston valve, a piston valve cylinder therefor, a cushioning piston connected with the piston valve, a cushioning piston cylinder within which the cushioning piston operates, means for by-passing pressures from one side of the cushioning piston to the other side of the cushioning piston within said cushioning piston cylinder, valve means for controlling said by-pass, and means cooperating with said valve means for entirely releasing pressure from said cushioning piston cylinder at each side of the cushioning piston valve.

CARL G. ASH.
